MACHINE FOR SURFACE-FINISHING PILOUS MATERIALS

George Frederick Farr, Luton, England

Application October 9, 1937, Serial No. 168,116
In Great Britain March 9, 1937

5 Claims. (CL 26—27)

This invention relates to machines for surface-finishing pilous materials, and is primarily concerned with means for imparting to felt hat materials finishing treatments known as "suedeing" and "ratinier effect."

In a machine according to the present invention for surface-finishing pilous materials, the material to be treated is engaged between a pair of pads at least one of which is driven for eccentric movement, there being provided a plurality of feed rollers at least one of which is driven for feeding the material between the pads, means being provided for bringing the pads into working engagement with the surface of the material.

With suedeing the material has a somewhat dull finish resembling that of suede, and for producing that finish the material needs to be fed fairly rapidly between the pads. On the other hand, with the ratinier effect, groups of close fibres are twisted up into separate little curls or tufts, and to produce that effect it is necessary that the material shall be fed past the pads relatively slowly; in fact the effect may even be improved if the material is held stationary between the pads for some few seconds and then moved on again step by step as small areas of the material are treated. In order that both suede and ratinier effects may be done on the one machine, it is contemplated that provision may be made for varying the rate at which the feed rollers operate, or even for rendering them ineffective.

In the accompanying drawings forming a part of this specification and in which like numerals are employed to designate like parts throughout the same:

Figure 1 is a side elevation of the machine according to the invention;

Figure 2 is a detail sectional side elevation showing how eccentric movement of the driven pad is effected.

As shown in Figure 1, the pad elements for operating upon the material comprise the eccentrically movable pad 3 and the axially movable pad 4. Both pads preferably have renewable coverings, and any convenient method of attaching such coverings may be employed. The pad 4 acts in the manner of a support for the material to be treated, while the pad 3 is eccentrically mounted so that it performs a substantially circular movement over the surface of the material resting on the pad 4. For convenience, it is generally preferred to have the pads mounted with their axes vertical. Adjacent the driven pad 3 is a driven feed roller 5, while adjacent the pad 4 is a freely rotatable feed roller 6. The

pad 4 is mounted for axial movement so that it, with the material resting on it, can be moved towards the driven pad 3. The pad 4 is borne upon the shaft 7, sliding in the bearing 8 extending from the main body casting 9 of the machine, and a treadle 10 is provided pivoted about the axis 11 and coupled to the axially movable shaft 7 by the links 12, 13 and 14 so that by pressing upon the treadle 10 the pad 4 may be caused to approach the driven pad 3. The arrangement is such that the pad 4 tends to remain in its lowermost position until the treadle 10 is operated to press it up. On the shaft 7 there is mounted a bearing 15 carrying a bracket 16 upon which the freely rotatable feed roller 6 is mounted. The buffer spring 17 is provided to give the supporting feed roller 6 some measure of resilience, while the end nut 18 can if desired be slackened off. When the axially movable pad 4 is raised to grip the material, the feed roller 6 will also approach the driven feed roller 5, causing the material to be gripped for feeding forward. If it is desired to render the feed rollers ineffective, the nut 18 can be slackened off and the free feed roller dropped.

It will be appreciated that so long as the pad 4 can be moved axially, taking the feed roller 6 upwards with it, there is no need for any drive to be imparted either to the pad 4 itself or to the feed roller 6, and it is therefore convenient to provide the driven pad 3 and the driven roller 5 on a projecting head casting 19 provided on the top of the body casting 9. The pad 3 is carried for eccentric movement with respect to the shaft 20 extending vertically through the head casting 19. On the shaft 20 is a pulley, indicated in broken lines by the reference numeral 21. Drive is transmitted to the shaft 20 by a belt, indicated at 22, which leads from the motor pulley 23 over the intermediate pulley, or preferably a pair of pulleys 24 mounted on the transverse axis. Conveniently, the driving means of the machine will comprise an electric motor, such as 25, mounted upon a support 26 adjustable by means of one or more bolts such as 27 for varying the tension of the belt 22.

The driven pulley 5, which is borne on a bracket 28 at each end of it, is driven by the flexible drive shaft 29 extending up from a reduction gearbox 30 provided on the end of the motor shaft remote from the pulley 23. One of the brackets 28 will preferably include the extension 31 serving to receive one end of the flexible drive shaft 29 from which the roller 5 will be driven, preferably by means of bevel gearing.

Although a satisfactory finish may be provided

with the ordinary substantially circular movement of the driven pad 3, it is preferred that the pad 3 shall be restrained against rotation about its own axis with respect to the shaft 20, and 5 there is therefore provided on the head 32 which carries the pad 3 a projection 33 bored for the reception of the rod 34 which is borne in the pivoted eye 35 extending down from the bracket 36. This arrangement is more clearly shown in the detail 10 view comprising Figure 2, and there is also shown in Figure 2 the bearing for the eye 35, which eye is carried on the rod 37 rotatable within the bracket 36, but resiliently supported therein by the spring 38. The spring 38 ensures that the 15 eye can find its own level with respect to the projection 33, and that there will thus be no need for accurately aligning the projection 33 with the eye 35 to prevent jamming of the rod 34.

In addition to showing more clearly and in 20 greater detail the means for restraining the free rotation of the head 32, Figure 2 also shows the eccentric axis 39 of the head which extends from the boss 40 mounted concentrically on the threaded portion 41 of the shaft 20.

25 It has been found that highly satisfactory results are produced where the work-supporting pad comprises a washleather cover over a metal head, and the reciprocating driven pad is comprised by a soft rubber covering over the steel head, the 30 rubber being itself covered with washleather. It can be considered therefore that it is desirable that the work-supporting roller should be of a fairly rigid nature, while the driven eccentrically 35 rotating roller which engages the actual surface under treatment shall be of a somewhat resilient nature. It may be mentioned that a washleather or similar skin material will produce the ratinier effect, but if an abrasive surface such as sandpaper is used, the finish will be sueded.

40 In operation, the material, or maybe the hat under treatment, is engaged over the work-supporting pad and between the feed rollers, after 45 which the treadle is operated to cause the work-supporting pad to approach the driven pad so that the material is gripped between the two pads.

In point of fact, the machine has been evolved 50 for working upon the surfaces of materials in the nature of fur-felt used in hat-making, but it will be appreciated that it can be applied equally well to the treatment of other textile materials.

For the suede-finish, the drive speed of the 55 shaft 20 would be from 1900 to 2500 R. P. M., whereas for the ratinier-finish that speed would 60 be reduced to about 800 R. P. M. with the feed roller speed reduced accordingly, but in some cases the feed rollers may be rendered ineffective when the machine is being used for the ratinier finish.

60 What I claim is:

1. A machine for surface-finishing hats made of felt and like pilous materials and for surface-finishing such materials, comprising a pad driven to move eccentrically but restrained against rotation and fixed in an axial sense; a cooperating pad movable in an axial sense only; means mounting said second pad for movement in said axial sense, treadle means for effecting movement of said pad-mounting means to cause axial movement of said cooperating pad to bring the pads into working engagement with the materials; a pair of feed rollers at least one of which is driven for feeding the material between said pads; means mounting one of said rollers adjacent said first pad; means mounting the other

of said feed rollers on said pad-mounting means to partake of movement therewith; driving means for effecting movement of the eccentrically movable pad and for driving through reduction gearing the driven feed rollers; said pads and feed rollers being in close proximity, of similar width, and both small relative to the area of material to be treated. 5

2. A machine for surface-finishing hats made from felt and like pilous materials and for surface-finishing such materials, comprising a pad driven to move eccentrically but fixed in an axial sense; a feed roller fixed transversely in the plane thereof but driven for rotation; a cooperating pad movable in an axial sense only and releaseably carrying a feed roller free for rotation about an axis in a plane transverse to that in which the co-operating pad moves; treadle means for effecting axial movement of said cooperating pad to bring said cooperating pad and the feed roller mounted thereon with the material on them into engagement with the eccentrically movable pad and driven feed roller respectively; said pads and feed rollers lying in close lateral proximity to the pads, of similar width, and all small relatively to the area of material to be treated; driving means for effecting movement of the driven pad member and for driving the driven feed roller through reduction gearing and a disconnectable flexible drive. 20 25

3. A machine for surface-finishing hats made from felt and like pilous materials and for surface-finishing such materials comprising a frame having an overhanging portion and a single pouncing or like finishing pad, supporting and driving means therefor comprising a mounting movably supporting it from said overhanging frame portion with the operative surface of said finishing pad facing downwardly and for movement of said pad so that any point on the operative surface of the pad moves in a substantially closed path whose plane is substantially coincident with the general plane of said operative surface and means for driving said pad at a suitable pouncing or surface-finishing speed, and 40 means for supporting the material against said driven pad and for feeding it along said plane at a speed and in a direction of movement independent of the speed and direction of movement of the surface of said pad, said feeding and supporting means comprising a member of relatively small effective area juxtaposed to said pad for supporting only a small portion of the material against the said pad whereby only a part of the material is at a time presented to said pad and other portions not being operated upon remain free from direct support and may hang freely and loosely downwardly from said supporting and feeding means, said feeding and supporting means having a driven surface of relatively small area and moving at a low speed for engaging a small portion of said material and effecting movement of successive relatively small portions of the material between said pad and member, whereby the operator, grasping the material, may, because of said relatively small effective areas, cause any or all parts of the material, irrespective of the shape or conformation of the latter, to be fed by said driven surface into operative relation to said finishing pad, a single column-like support having sleeve-like means fixed relative to said frame for movably mounting and guiding said support for movement in a general up and down direction and toward or away from said single driven pouncing pad, means 60 65

70 75 80 85 90 95 100

column-like support having sleeve-like means fixed relative to said frame for movably mounting and guiding said support for movement in a general up and down direction and toward or away from said single driven pouncing pad, means 75

mounting said feeding and supporting means on said single column-like support, and means manually controllable for moving said support and hence said feeding and supporting means upwardly or downwardly and hence toward or away from said single driven pouncing pad and for thereby controlling the pressure with which the material is held against the surface of said driven pad and the pressure with which it is held against said driven surface to affect respectively the operation of said driven pad upon the material and the feeding action of said driven surface upon the material.

4. A machine as claimed in claim 1 in which the means mounting said feed roller onto said pad-mounting means comprises a connection that is resilient and that can yield as said pad-mounting means moves said roller to press the material against the other roller.

5. A machine for surface-finishing hats made from felt and like pilous materials and for surface-finishing such materials comprising a pouncing or like finishing pad, supporting and driving means therefor comprising a mounting movably supporting it for movement so that any point on the operative surface of the pad moves in a path whose plane is substantially coincident with the general plane of said operative surface and means for driving said pad at a suitable pouncing or surface-finishing speed, and means for supporting the material against said driven pad and for feeding it along said plane at a speed and in a direction of movement independent of the speed and direction of movement of the surface of said pad, said feeding and supporting means comprising a member in the form of a co-

operating pad free from driving movement and of relatively small effective area juxtaposed to said pad and exposed upwardly toward the latter together with a feed roller positioned adjacent said member and also of relatively small effective area so that said member and said adjacent feed roller support only a small portion of the material against the said first pad whereby only a part of the material is at a time presented to said first pad and other portions not being operated upon remain free from direct support by said member and roller and may hang freely and loosely downwardly therefrom, a cooperating feed roller having means mounting it adjacent said first pad and substantially juxtaposed to said first-mentioned feed roller and also of relatively small effective area, movable column-like means mounting said second pad and its adjacent feed roller and guiding means for said movable means for guiding it for movement in a direction to move said second pad and its adjacent feed roller as a unit toward and away from said first pad and said second-mentioned feed roller respectively, means for driving at least one of said feed rollers to effect a feeding movement of the material when a small portion of the latter is gripped between said two feed rollers and an adjacent portion is pressed by said cooperating pad into operative relation to said first pad, and treadle means for controlling movement of said movable column-like mounting means and hence movement of said cooperating pad and its adjacent feed roller toward or away from said first pad and said second-mentioned roller respectively.

GEORGE FREDERICK FARR.
